LLP

(57) **CLAIM**

The ornamental design for a picture frame, as shown.

DESCRIPTION

FIG. 1 is an elevated, perspective view of the picture frame in accordance with my invention;

FIG. 2 is a front view of the picture frame; and,

FIG. 3 is an exploded perspective view of the picture frame.

The broken lines are for illustrative purposes only and form no part of the claimed design.

1 Claim, 3 Drawing Sheets

FIG. 1

FIG. 2

FIG. 3
